Atty.

UNITED STATES PATENT OFFICE.

LINDON WALLACE BATES, OF MOUNT LEBANON, NEW YORK.

APPARATUS FOR AGITATING AND HEATING MOBILE MATERIAL.

1,406,818.

Specification of Letters Patent. Patented Feb. 14, 1922.

Application filed December 10, 1919. Serial No. 343,983.

To all whom it may concern:

Be it known that I, LINDON W. BATES, a citizen of the United States, residing at Mount Lebanon, in the county of Columbia 5 and State of New York, have invented certain new and useful Improvements in Apparatus for Agitating and Heating Mobile Material, of which the following is a specification.

10 This invention pertains to an apparatus for agitating and heating mobile material stored in bulk and is designed more particularly to cause or effect a constant or periodic agitation or flow in a stored body 15 of mobile fuel. The fuel may be oil, tar or a blend of several liquid hydrocarbons. So also the fuel may be oil having asphaltic or carbon particles as natural impurities which it is desired to retain in suspense, or the fuel 20 may be a composite of pulverized carbonaceous particles and liquid hydrocarbon. In such composites containing particles or immiscible droplets above colloidal size, sedimentation or settling proceeds naturally 25 when the fuel is at rest, unless artificial stabilizing treatment has been given, as by the addition of certain stabilizing agents, for instance, mineral soaps, coal derivatives, or chlorine gas and by the proper blending 30 of the components. Agitation also delays or prevents separation of the components or recombines them and may to a limited extent be resorted to instead of the addition of such agents and treatment, or to reduce 35 the amount of agent used or duration of the treatment. Artificially induced stability may be renewed in this way or its termination deferred. In general, wherever agitation is useful to temporarily retain particles 40 or droplets in suspension in a liquid medium, this invention indicates an improved way to agitate. Furthermore since heating the medium reduces its viscosity and hence augments the tendency to separation, the apparatus hereafter described operates to overcome to some extent this effect. Circulation 45 is quite effective to accomplish the desired result, and it may be accelerated or reduced in speed by elevating or lowering the heat 50 applied to the parts.

Aside from causing a circulation the apparatus is a convenient way of transmitting heat as it embodies a large heating area in small space and well distributed. It is superior to coils or ordinary pipes carrying

steam or hot water. As practically all heavy oils and composites have to be preheated in storage in order to flow and be atomized in burners or otherwise dealt with, the present invention describes a convenient way of so heating the fuel or other material.

A simple embodiment of the invention is illustrated in the annexed drawings, wherein:

Fig. 1 is a vertical longitudinal sectional view of a tank with the heat applying means positioned therein;

Fig. 2 a transverse vertical sectional view;

Fig. 3 an enlarged sectional elevation of a portion of the heat distributing and current initiating element; and

Fig. 4 a detail view of an alternative form of one of the distributing elements.

In the drawings, 1 denotes a tank which may be of any desired form for land or marine storage, but which, by preference, will be curved (circular) in cross section to prevent the formation of angles or pockets which would have a tendency to produce stagnation and a consequent sedimentation. 75 The tank is provided with a suitable man-hole 2, a filling pipe 3 and a discharge or off-take pipe 4, the latter extending well down toward the lowermost portion of the tank and preferably terminating in a T 5. Heating pipes extend into the tank and in the particular arrangement shown comprise two inlet pipes 6 and 7, a discharge pipe 8 and laterals 9 and 10 which connect pipes 6 and 7 respectively with the discharge pipe 8. 80 Lateral 9 preferably passes through the T 5 in spaced relation thereto thereby imparting heat directly to the fuel mixture at such point, ensuring and assisting in the ready outflow of the fuel through the discharge 85 pipe 4.

Each of the vertically disposed pipes 6, 7 and 8 will preferably be provided with a plurality of heat dispersion and current producing elements. The elements are 100 formed of metal so as to readily absorb and conduct the heat from the supporting pipes and give it off to the liquid fuel in which they are submerged. Each element 11 is of substantially inverted cone shaped form 105 and is provided with a sleeve 12 which closely fits the heating pipe, being secured thereto by a set screw 13, or other suitable fastening means. The uppermost element or deflector of each series is preferably im- 110

perforate, but the wall of each of those below is provided with perforations as 14 and the deflectors are so secured to the pipes that the openings in one stand in a staggered relation to those immediately above and below. The heating medium, such for instance as hot water or steam passing down the pipes 6 and 7 through the laterals 9 and 10 and up pipe 8, heats said pipes and consequently heats the fuel surrounding the same. Such heating will induce a flow in the fuel, the warmed or heated portion tending to rise, with a consequent falling of the relative cool portion. The deflectors moreover are heated and transmit and give off the heat to the surrounding fuel body. By reason of their formation the rising warmed fuel will be deflected outwardly away from the pipes and deflectors and by reason of the staggered relation of the openings 14 the rising fuel mass is broken up into a series of outwardly flowing or directed currents and prevented from rising directly to the upper portion of the tank. The flow thus produced is indicated by the arrows, Figs. 1 and 2, from which it will be seen that the entire body or mass of fuel is kept in a constant state of agitation or movement. As a consequence separation is prevented or delayed and the fuel leaves the tank warmed or heated to a greater or less degree. The application of the heat may be continuous or periodic as the physical characteristics and the conditions of use may determine and require. The heat and circulation of the liquid may either or both be controlled to a certain extent by the number, size and spacing of the elements 11. By modifying the curvature of the elements 11 one may also govern the circulation, and in Fig. 4 I have shown an element, the walls whereof are curved instead of straight.

What is claimed is:—

1. In an apparatus of the character specified, the combination of a tank; a supply pipe; an outlet pipe; a heat conducting pipe located within the tank; and a member in surface contact with the said last named pipe from which member a part extends laterally for conducting heat from the said pipe and initiating currents from the outer surface of the said member in the material within the tank.
2. In an apparatus of the character specified, the combination of a tank; a supply pipe; an outlet pipe; a heat conducting pipe extending into and out of the tank; and a series of heat conducting deflectors carried by said last named pipe on its outer surface.
3. In an apparatus of the character specified, the combination of a tank; a supply pipe; an outlet pipe; a heat conducting pipe located within the tank; and a series of heat conducting deflectors carried by said last

named pipe on its outer surface, said deflectors in part at least being provided with openings located away from the center extending therethrough.

4. In an apparatus of the character specified, the combination of a tank; a supply pipe; an outlet pipe; a heat conducting pipe located within the tank; a series of heat conducting deflectors carried by said last named pipe, said deflectors in part at least being provided with openings extending therethrough, the openings in one deflector being staggered with reference to those in the next adjacent deflector.

5. In an apparatus of the character specified, the combination of a tank; a supply and an outlet pipe; a heat conducting pipe located within the tank; and a series of inverted cone shaped deflectors carried by said last named pipe on its outer surface.

6. In an apparatus of the character specified, the combination of a tank; a supply and an outlet pipe; a heat conducting pipe located within the tank; and a series of inverted cone shaped deflectors carried by said last named pipe on its outer surface, said deflectors in part at least being provided with openings located away from the center extending therethrough.

7. In an apparatus of the character specified, the combination of a tank; a supply and an outlet pipe; a heat conducting pipe located within the tank; and a series of inverted cone shaped deflectors carried by said last named pipe, said deflectors in part at least being provided with openings extending therethrough, the openings in one deflector being staggered with reference to those in the next adjacent deflector.

8. In an apparatus of the character specified, the combination of a tank curved in cross section; an inlet and an outlet therefor; a heating pipe extending vertically therein; and a plurality of inverted cone shaped deflectors carried on the outer surface thereof, some of said deflectors being provided with openings located away from the center extending therethrough.

9. In an apparatus of the character specified, the combination of a tank substantially circular in cross section; an inlet pipe; an outlet pipe terminating short of the lower portion of the tank; a T secured to the lower end of said outlet pipe; a heating pipe extending into the tank and through the T, thence out of the tank; and a series of deflectors carried by the heating pipe.

10. In an apparatus of the character specified, the combination of a tank substantially circular in cross section; an inlet pipe; an outlet pipe terminating short of the lower portion of the tank; a T secured to the lower end of said outlet pipe; a heating pipe extending into the tank and through the

T, thence out of the tank; and a series of inverted cone shaped deflectors carried by the inlet and outlet sections of the heating pipe.

11. In an apparatus of the character specified, the combination of a tank substantially circular in cross section; an inlet pipe; an outlet pipe terminating short of the lower portion of the tank; a T secured to the lower end of said outlet pipe; a heating pipe extending into the tank and through

the T, thence out of the tank; and a series of inverted cone shaped deflectors carried by the inlet and outlet sections of the heating pipe, said deflectors in part at least being provided with openings extending therethrough. 15

In testimony whereof I have signed my name to this specification.

LINDON WALLACE BATES.
